[57] CLAIM

I claim the ornamental design for a combined hanger and hook, as shown.

DESCRIPTION

FIG. 1 is a front/left-side/bottom perspective view of a combined hanger and, in a closed position, hook showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is a front/left-side/bottom perspective view of the hanger shown separately for clarity of illustration;

FIG. 9 is a front elevational view of the hanger thereof;

FIG. 10 is a rear elevational view of the hanger thereof;

FIG. 11 is a left-side elevational view of the hanger thereof;

FIG. 12 is a right-side elevational view of the hanger thereof;

FIG. 13 is a top plan view of the hanger thereof;

FIG. 14 is a bottom plan view of the hanger thereof;

FIG. 15 is front/right-side/bottom perspective view of the hook in the open position shown separately for clarity of illustration;

FIG. 16 is a front elevational view of the hook thereof in the open position;

FIG. 17 is a rear elevational view of the hook thereof in the open position;

FIG. 18 is a left-side elevational view of the hook thereof in the open position;

FIG. 19 is a right-side elevational view of the hook thereof in the open position;

FIG. 20 is a top plan view of the hook thereof in the open position; and,

FIG. 21 is a bottom plan view of the hook thereof in the open position.
